(57) **CLAIM**

The ornamental design for a set of microphone, receiver and charging case as shown and described.

DESCRIPTION

FIG. 1 is a front, right and top perspective view of a charging case of a set of microphone, receiver and charging case of FIG. 28 showing my new design, shown separately for ease of illustration.

FIG. 2 is a rear, left and bottom perspective view thereof.
FIG. 3 is a front, left and top perspective view thereof.

FIG. 4 is a front elevation view thereof.

FIG. 5 is a rear elevation view thereof.

FIG. 6 is a left side elevation view thereof.

FIG. 7 is a right side elevation view thereof.

FIG. 8 is a top plan view thereof.

FIG. 9 is a bottom plan view thereof.

FIG. 10 is a front, right and top perspective view of the receiver of the set of microphone, receiver and charging case of FIG. 28, shown separately for ease of illustration.

FIG. 11 is a rear, left and bottom perspective view thereof.
FIG. 12 is a front elevation view thereof.

FIG. 13 is a rear elevation view thereof.

FIG. 14 is a left side elevation view thereof.

FIG. 15 is a right side elevation view thereof.

FIG. 16 is a top plan view thereof.

FIG. 17 is a bottom plan view thereof.

FIG. 18 is a front, right and top perspective view of the microphone of the set of microphone, receiver and charging case of FIG. 28, shown separately for ease of illustration.

FIG. 19 is a rear, left and bottom perspective view thereof.
FIG. 20 is a front elevation view thereof.

FIG. 21 is a rear elevation view thereof.

FIG. 22 is a left side elevation view thereof.

FIG. 23 is a right side elevation view thereof.

FIG. 24 is a top plan view thereof.

FIG. 25 is a bottom plan view thereof.

FIG. 26 is an enlarged view of detail 26 in FIG. 2.

FIG. 27 is a perspective view of a charging case of a set of microphone, receiver, and charging case, shown separately for ease of illustration thereof, in a closed position; and,
FIG. 28 is a perspective view of a microphone, receiver, and charging case of a set of microphone, receiver, and charging case, in an open position thereof.

The dashed broken lines depict portions of the set of microphone, receiver and charging case that form no part of the claimed design.

The dot-dash broken lines in FIGS. 2 and 26 depict the boundaries of the enlarged views and form no part of the claimed design.
